UNITED STATES PATENT OFFICE.

HERBERT H. STEELE, OF MARCELLUS, NEW YORK, ASSIGNOR TO THE MONARCH TYPEWRITER COMPANY, OF SYRACUSE, NEW YORK, A CORPORATION OF NEW YORK.

TYPE-WRITING MACHINE.

1,106,744.

Specification of Letters Patent. Patented Aug. 11, 1914.

Application filed March 29, 1913. Serial No. 757,532.

To all whom it may concern:

Be it known that I, HERBERT H. STEELE, citizen of the United States, and resident of Marcellus, in the county of Onondaga and State of New York, have invented certain new and useful Improvements in Type-Writing Machines, of which the following is a specification.

My present invention relates to case shifting mechanism for typewriting machines and its general object is to provide new and improved mechanism of the character specified.

More specifically one object of the invention is to provide mechanism that is automatically operative to change case or vary the relationship between the platen and printing elements so that different characters on the latter may be employed.

Another object is to provide case shifting devices automatically operative at predetermined points in the travel of the carriage.

Another object is to provide case shifting devices automatically operative by tabulating mechanism.

Another object is to provide type bar shifting mechanism operative in the manner and by the means above specified.

To the above and other ends my invention consists in the features of construction, combinations of devices and arrangements of parts hereinafter described and particularly pointed out in the claims.

In the accompanying drawings, Figure 1 is a fragmentary end view partly in section of a Monarch typewriting machine embodying one form of my invention. Fig. 2 is a fragmentary sectional view taken on a plane indicated by the dotted line *x* in Fig. 1 and looking in the direction of the arrow at said line. Fig. 3 is a view corresponding to Fig. 2 but showing the parts in different relations, some of the parts shown in Fig. 2 being omitted. Figs. 4 and 5 are operating views showing some of the parts of Fig. 2 in different relations. Fig. 6 is a fragmentary central sectional view taken fore and aft of a No. 11 Remington typewriting machine embodying a modification of my invention. Fig. 7 is a fragmentary vertical sectional view taken on a plane indicated by the dotted line *v* in Fig. 6 and looking in the direction of the arrow at said line.

Referring first to the construction shown in Figs. 1 to 5, inclusive, the main frame

comprises a base 1, posts 2 and a top plate 3 above which are fixed grooved track-ways 4 which coöperate through anti-friction balls 5 with the grooved rear bar of a traveling carriage 6 on which is mounted a rotary platen or platen element 7. The carriage is constantly impelled leftward by a motor or spring drum 8 with which it is connected by a band or strap 9, leftward movement being, however, controlled by carriage feeding devices comprising a feed rack 10 secured to arms 11 pivoted at 12 on the carriage, said rack normally meshing with a feed pinion 13 which is supported on the forward end of a shaft 14, said shaft bearing in a bracket 15 secured to the top plate. Operatively connected with said shaft is a toothed escape-wheel 16 with which coöperate dogs or detents 17 and 18 mounted on a carrier or rocker 19 which is actuated from the printing keys by devices not herein shown but which are preferably of the usual construction found in the Monarch typewriting machine. Coöoperative with the front face of the platen are printing elements or type bars 20, each type bar being provided at its free end with a type block 21 provided with a lowercase type 22 and an uppercase type 23. Each type bar is pivoted at 24 on a hanger 25 which is secured by a screw 26 to the front face of a shiftable element or segment 27. The type bars and hangers are circularly arranged at the front face of the segment which is vertically disposed, and the free ends of the type bars are supported normally by a curved rest 28 which is mounted on arms 29 secured to the segment 27, the construction being such that when the segment is shifted up and down to change case, as it is called in the art, that is to bring one of the sets of types 22 or 23 into use while carrying the other out of use, the type bars will move bodily up and down with the segment or support 27 without their relationship with said support being substantially varied. A machine of this style in which the type bars are shifted or varied in their normal positions to effect a change of types or change of case is known variously as a type bar shifting, or segment shifting or type basket shifting machine. The actuating devices for each type bar comprise a link 30 which connects the type bar with the upper end of a sub-lever 31 slotted at its lower end at 32 to coöperate with a fixed abutment or

guide 33. The sub-lever is pivoted at 34 on a key lever 35 fulcrumed at its rear on a plate 36 and provided at its upturned forward end with a key cap 37. An actuation of any key lever will, through the described mechanism, cause the connected type bar to swing to the printing point to coöperate with the platen through a ribbon (not shown). Each type bar is provided with a restoring spring 38. When the type bars are shifted to change case the links 30 swing about their points of connection with the sub-levers 31 as centers so that the sub-levers and key levers are not affected by case shifting operations.

The segment or type bar support is provided at its ends with upright grooved guide ways 39 which coöperate through anti-friction rollers 40 with grooved track-ways formed in the inner faces of upright posts 20 or standards 41 which are secured to the base of the machine. The segment is adapted to be shifted up and down on the posts or guides by key controlled devices of ordinary construction comprising arms or links 42 connected at 43 to the lower part of the segment. Each arm 42 is pivotally connected at 44 to a crank arm 45 which is secured to a rock shaft 46 and is supported at its ends from the sides of the base. Projecting forward from the rock shaft 46 quite close to each end thereof is a crank arm 47 to which is adjustably secured by a screw 48 a second crank arm 49 provided at its end with a roller 50 which coöperates with the under edge of a shift lever 51, said shift lever having a fixed fulcrum 52 and being provided at its rear end with a restoring spring 53 and at its front end with a key 54. There are two of these keys one at each side of the lower bank of keys in the keyboard of the machine and each is operated through the described train of connections to shift the segment upward so that the uppercase types on the type blocks may be rendered effective. There is also provided at the left end of the upper bank of keys a shift lock key 55 which operates a lever 56 to lock the segment in uppercase position, from which it may be released by an actuation of the left-hand key 54. Each of the keys 54 when actuated independently operates to shift the segment temporarily, said segment when released returning to normal position under the impulse of gravity which is sufficient to overcome the effect of the usual counterbalancing spring 57, one end of which is connected to a pin 58 on the rock shaft 46 and the other end of which is anchored fixedly. Stop devices are provided for limiting the up and down shifting movements of the segment, said devices comprising lugs or stops 59 and 60 projecting rearwardly from the segment 27 at its ends. Coöperative with the stop lugs 59 and 60 are stop arms 61 and 62 adjustably secured by

screws 63 to the posts 41. There are two sets of these stop devices one at each end of the segment. Under normal conditions the stops 59 coöperate with the inner ends of the stops 61 as shown in Fig. 2, thus limiting the downward movement of the segment. When the segment is shifted upward it is arrested and the extent of its shift movement determined by the engagement of the stops 60 with the inner ends of the stops 62 as shown in Fig. 3. The case shifting mechanism as thus far described is the regular shifting mechanism of the Monarch typewriter.

Denominational tabulating mechanism of the usual construction is provided, said mechanism comprising a toothed stop bar 64 supported on lugs 65 secured to the carriage 6 and receiving one or more adjustable column stops 66 (Fig. 2). Coöoperative with the column stops are denominational stop levers 67 pivoted at 68 on a frame 69 detachably secured to the main frame of the machine. The lower ends of the stop levers 67 are actuated by slide bars 70 which in turn are pushed rearward by crank arms 71 secured to rock shafts 72 on a frame 73 detachably mounted on the main frame near the front thereof. Said rock shafts are actuated by crank arms or key levers 74, each provided with a tabulator key 75, which, when operated, acts through the described mechanism to project the upper end of the associate stop lever 67 forward into the path of the column stops. Each stop lever 67 when operated also releases the carriage from its step-by-step feeding devices through releasing mechanism comprising a universal bar or bail 76, the horizontal body portion whereof is arranged behind the lower arms of the levers 67. The end portions of said bail are pivoted at 77 and one of them has a forward extension 78 connected by a link 79 to a lever 80 which operates a rack lifter 81 to swing the feed rack 10 up out of mesh with the feed pinion 13, thus freeing the carriage for continuance leftward movement under the pull of the spring drum 8. Such movement or tabulating run will continue until the carriage is arrested by the coöperation of the projected stop lever 67 with the proximate column stop 66.

Referring now particularly to the novel parts of the present construction it has been found desirable in some kinds of typewriting as in way-billing to write the data, other than the numbers, in capital letters because the size of the capitals renders them easier to read. These capital letters in case shift machines are so placed on the type bars as to require a case shifting operation to enable them to be used. Numeral characters, on the other hand, are usually in the lower-case position on the type bars and are brought into use without the shifting. Consequently when

the usual typewriting machine is employed for work of the character specified, considerable time is wasted in the case shifting operation, it being necessary, say, to shift 5 the type basket, or the platen as the case may be, to enable the first portion of a line to be written in capitals and then to shift back to lower-case position in order to enable the numerals, usually at the right-hand side of 10 the sheet or the latter portion of the line, to be written in. As a result special machines have been provided having single type bars, the types being capitals, usually gothic, and the small letters or lower-case types being 15 eliminated except that the numeral types are retained; but of course these special machines are not adapted for ordinary typewriting.

The chief object of the present embodiment of my invention is to provide a case shifting machine of regular construction with means for enabling it to be used for ordinary typewriting and also for writing way-bills or other similar typewriting in 20 the way specified above as desirable, that is, in writing the parts of the lines in uppercase types or capitals and other parts of the same line in lowercase types, usually numerals. In carrying out this object in the present 25 instance, I provide devices for automatically shifting the type basket up and down, these devices being actuated by a special stop which may be adjusted as desired on the column stop bar 64, said stop operating, when 30 the carriage is moving in one direction, to shift the type basket to the uppercase position at a predetermined point in the travel of the carriage or in the printing line, while during the travel of the carriage in the opposite 35 direction the reverse case-shifting operation takes place and the type basket shifts back to normal or lowercase position. This automatic case shifting mechanism does not interfere with the operation in the ordinary 40 way of the regular key operated case shifting mechanism heretofore described; and furthermore the key operated devices may be actuated at any time without interfering with the automatic devices. Said automatic 45 devices, in the present instance, comprise a rock shaft 82 arranged fore and aft of the machine at the right-hand side. Said rock shaft bears at its forward end in a hole in the right-hand post 41, the hole being formed 50 in the rear face of the post between the stops 61 and 62. The rear end of said shaft bears in a bracket or arm 83 secured by screws 84 to the right-hand rear post 2, as best appears in Fig. 2, which is a rear view. Fixed to the 55 rock shaft 82 near its forward end is a crank arm 85, said crank arm extending horizontally inward and underlying a stud or pin 86 which is fixed in the segment 27 and projects rearwardly therefrom in position to be engaged by the arm 85. The rear end por-

tion of the shaft 82 has fixed to it a crank arm 87, said crank arm extending inward and having pivotally connected to it at 88 the lower end of an upright link 89, the upper end whereof is pivotally connected at 90 70 to the short horizontally disposed arm of a bell crank 91 pivoted at 92 to an angular bracket 93 screwed at 94 to the underside of the top plate. The longer or upright arm of the bell crank 91 has pivotally connected to it at 95 the right-hand end of a link 96 which extends leftward under the top plate and is pivotally connected at 97 with the lower arm of a lever member designated as a whole as 98. Said lever member extends 75 downward through an opening 24 in the top plate and is fulcrumed on a headed and shouldered screw 99 which is secured to the rear face of the bracket 15. The upper arm of the member 98 is enlarged, as indicated 80 at 100, the enlargement being formed with an arcuate slot or opening 101 which fits over the barrel portion 15^a of the bracket 15. The outer left-hand face of the portion 100 is formed on a curve having as a center the axis of rotation of the lever 98, the curved face 102 terminating at its lower end in a stop face 103 and at its upper end in a lug or engaging portion or device 104. This lug is adapted for coöperation with a special 85 column stop 105 which differs from the ordinary column stop 66 in that its forward side extends downward as indicated at 105^a below the stop bar 64 and into position to co-operate with the lug 104 during movements 90 of the carriage. In other respects the stop 105 is like the ordinary stop 66 and may be adjusted as desired along the stop bar. 95

Pivoted on the shouldered screw 99 between the head thereof and the member 98 is a trip member 106 terminating in an upwardly extending tooth or engaging portion 107 and having a cut out 108 adapted to engage at times with the barrel portion 15^a. This trip is adapted to act on and is connected by a draw spring 109 with a pivoted latch 110, one end of the spring being hooked over a pin 111 on the trip and the other end over a pin 112 on the latch. The latch 110 is of sufficient width at its upper or free end to coöperate both with the trip 106 and with the lever member 98. Said latch is arranged at the left of said lever member and is pivoted at its lower end on a headed and shouldered screw 113 which is supported on an angular bracket 114, said bracket being screwed at 115 to the top plate. The spring 109 tends constantly to swing the trip 106 leftward about its pivot and also to draw or swing the latch 110 downward around its pivot toward the right. Referring to Fig. 2 it will be observed that the swinging movement of the trip 106 is controlled and limited in one direction by a stop pin 116 projecting rear- 100

105

110

115

120

125

130

ward from the portion 100 of the member 98 while downward swing of the latch 110 is limited by its engagement with the upper face of the trip. The latch and the trip are also adapted to be limited in their movements under the influence of the spring by other devices, as will hereinafter appear.

The operation of the automatic case shift mechanism above described may be briefly explained. Let it be assumed that the parts are positioned as in Figs. 1 and 2 and that the platen carriage is being restored from left to right in the direction of the arrow in Fig. 2, preliminary to beginning a new line of writing. It will be apparent that as the rightward movement of the carriage continues the extension or device 105^a will engage with the lug 104 and force said lug rightward to the position shown in Fig. 3.

As a result of this movement the lever member 98 will be turned on its fulcrum, causing the link 96 to operate the bell crank 91 which in turn will pull upward on the link 89. Said link acting through the crank arm 87 will rock the shaft 82 to cause the crank arm 85 at the forward end thereof, acting against the pin 86, to shift the segment 27 upward until it is arrested in uppercase position by the coöperation of the stops 60 with the stationary stops 62, as illustrated in full lines in Fig. 3. As soon as the extension or device 105^a clears the lug 104 it will cease to transmit motion to the member 98, although the movement of the carriage

will continue until the beginning of the line is reached. The member 98 will be maintained in the Fig. 3 position by the latch 110. This latch, during the movement of the member 98 from the Fig. 2 to the Fig. 3 position, will ride over the face of the trip 106 back of the tooth 107 until said trip, which swings with the member 98 during part of its movement under the influence of the spring 109, passes out of engagement

with the latch whereupon the latch will drop down on to the curved face 102 of the member 98 and will follow said face until it in turn passes out of engagement with the latch. As soon as this occurs the latch will be drawn down by the spring 109 to engage, as shown in Fig. 3, with the corner formed by the faces 102 and 103. The end 110^a of the latch is so shaped with respect to said corner that when the member 98 is finally

arrested in the Fig. 3 position by reason of the co-action of the stops 62 and 60, said corner will hold the latch in the Fig. 3 position. It will be understood that the trip 106 participates in the movement of the member 98 as described by reason of the pull of the spring 109 and owing to the movement of the stop pin 116 with the member 98, the displacement of the stop pin permitting the spring to turn the trip until it is arrested by the engagement of the cut-out

108 with the barrel 15^a as in Fig. 3. The member 98, however, continues moving after the arrest of the trip 106, so that when the member 98 is finally arrested the stop 116 will be separated from the trip, as will be seen from Fig. 3. At this time the trip will be slightly separated from the upper end 110^a of the latch 110, which is in locking engagement with the corner formed by the faces 102 and 103. From the described operation it will be understood that the member 98 and the latch 110 coöperate to maintain each other in the Fig. 3 position, and that by reason of the locking or latching of the member 98 as described, the segment will be maintained locked or latched in the uppercase position where the capital types 23 will be caused to print by the operation of the type bars. As a result, if writing be begun after the return of the carriage from left to right as described, such writing will be done by the uppercase types or capital letters until the carriage, in the course of its travel from right to left, brings the special stop 105 again into co-operation with the automatic shifting mechanism. This coöperation will take place between the extension or engaging portion 105^a and the tooth 107 of the trip 106 as shown in Fig. 4.

Prior to engaging the tooth 107 the extension 105^a passes over the lug 104 but without coöoperating with it, the lug at this time being below the path or plane of the said extension. Such movement of the stop 105 may be brought about by reason of letter space movements of the carriage but under ordinary conditions it will take place rather through a tabulating run of the carriage since the data at the beginning of the line printed in capital or uppercase types will not occupy the entire space between the left-hand margin of the sheet and the column in part defined by the special stop 105. Whether, however, the stop is moving toward the left (or in the direction of the arrow in Fig. 4, the latter being a rear view) step by step or during a tabulating run, said extension 105^a will engage with the tooth 107, and as the movement of the carriage continues will force the trip 106 leftward, causing the trip to engage with the latch 110 and forcing said latch leftward against the pull of the spring 109 to the position shown in Fig. 4. From this figure it will be observed that the latch 110 has been forced out of engagement with the corner of the portion 100, leaving the member 98 free. The freeing of said member as described releases the segment 27, which will be restored by gravity to the normal or lowercase position as illustrated in Fig. 2; and this movement will result in swinging the member 98 from the Fig. 4 to the Fig. 5 position through the train of connecting devices.

During this movement of the member 98 the pin 116 will engage with the trip 103 and will force said trip back with it to the position shown in Fig. 5. The trip is shaped 5 to provide a cam surface 103^a which will act on the latch 110 during the movement of the trip from the Fig. 4 to the Fig. 5 position to force or cam said latch upward on to the rounded upper face of the trip which connects the cam face 103^a with the tooth 107.

As a result of the described operations it will be understood that when the carriage is next arrested and printing operations are begun, said printing operations will take 10 place from the lowercase types 22 since the type support or segment 27 has been restored to the lowercase position. Also the devices comprising the member 98, trip 103 and latch 110 have been restored to the position 15 in Fig. 2, Fig. 5 corresponding, in so far as it relates to these parts, with Fig. 2. It will also be understood that during further movements of the carriage from right to left the parts will remain in the described 20 positions and the printing will be from the lowercase types; and that when the carriage is next restored from left to right to begin a new line the cycle of operations hereinbefore described will be repeated. Thus it 25 will be seen that a relative shifting movement between the type elements or type bars and the platen element or platen takes place automatically at predetermined points during to and fro movements of the traveling 30 carriage and that this automatic operation is effected by a train of devices which are actuated by part of the tabulating mechanism. The extent of the shifting movement will be 35 apparent from a comparison of the full and dotted line positions of the upper edge of the segment in Figs. 2 and 3.

While the case shifting operation or relative shift or movement between the printing and type bar elements necessary to effect a 40 change of case takes place in the construction heretofore described through a shifting movement of the type bar elements or printing instrumentalities, the invention is equally applicable to a construction where- 45 in such relative movement is effected through a shifting movement of the platen element instead of the type bar elements. Such a construction in which the platen element is shifted is exemplified in Figs. 6 and 7 which 50 illustrate another form of my invention applied to a No. 11 Remington typewriting machine. Said Remington machine has a main frame which includes a base 117, posts 118 and a top plate 119 above which are 55 fixed grooved track-ways 120 that coöperate through anti-friction balls 121 with the grooved front and rear bars 122 and 123 of a rectangular truck which further comprises connecting end bars 124. Shiftably con- 60 nected with said truck by arms or links 125

is a platen frame or carrier which comprises end bars 126, a connecting cross bar 127 and a cross rod 128. Supported rotatably on said platen frame is a platen or platen element 129. The platen carriage comprising 70 the truck and the platen frame is urged leftward by a carriage motor or spring drum 130 which is connected by a strap 131 with the carriage.

A feed rack 132 mounted on arms pivoted 75 to the truck meshes normally with a pinion 133 which is secured to a shaft 133^a that bears in a stationary bracket 134, said shaft being connected with escapement devices 80 of the ordinary construction not disclosed herein. The platen and platen frame may be shifted together at will at any point in the travel of the carriage. To this end a roller 135 that is mounted on the cross bar 127 runs on a shift rail 136 which is comprised in a shift frame that further includes end bars 137 and a cross bar 138 from the ends whereof depend arms or bars 139 having their lower ends pivotally connected at 140 with levers 141 fulcrumed on a rod or 90 shaft 142 supported in the sides of the base. The forward arms of said levers 141 are connected by a bail or cross piece 143 which is operative from shift key levers 144 each provided with a key 145. An operation of 95 either of the keys 145 elevates the shift frame comprising the rail 136, raising the platen frame and carriage to uppercase position without affecting the carriage truck. A counterbalancing spring 146 which assists 100 the shifting movement is connected to a pin 147 on the bail 143, the rear end of said spring being anchored to a stationary pin 148. The type bars 149 are each provided with a lowercase type 150 and an 105 uppercase type 151 and normally rest at their free ends on a support 152. Each type bar is pivoted in a hanger 153 which is secured to the front face of a stationary support or segment 154. The type bar actuating devices for each type bar comprise a link 155, a lever 156 and a second link 157. The link 157 is connected with a key lever 158 fulcrumed at 159 and provided with a key 160. Each key lever is also provided 110 with a restoring spring 161 and operates through the described connections to actuate the associate type bar, causing one or another of the types 150 and 151 thereon to coöperate with the front face of the platen 115 through a ribbon (not shown), the coöperating type depending on the shift position of the platen. The machine is provided with tabulating mechanism of the usual construction comprising a toothed column stop bar 120 mounted on arms 163 extending rearward from the carriage truck, said stop bar 125 adjustably supporting one or more column stops 164 of ordinary construction. Adapted to coöperate with the column stops are 130

denominational stop levers 165 pivotally supported at 166 on a stationary bracket or frame 167, said levers being connected at their lower ends with push rods 168 each 5 of which is provided with a key 169 and a restoring spring 170. Each push rod 168 is provided with a collar 171 which is adapted to actuate carriage releasing devices comprising a pivoted bail 172 connected by 10 links 173 with a crank arm 174 fixed to a rock shaft 175 to which is also fixed an angular arm 176 that is connected through a link 177 with a releasing lever 178 that at its forward end underlies the rack 132 and 15 is adapted to lift the same out of mesh with the pinion 133 when one of the tabulator keys 169 is operated. It will be understood that the operation of such key projects the upper end of the associate stop lever 165 20 into the path of the column stops 164 on the carriage and also releases the carriage from its escapement devices so that said carriage will move freely leftward under the influence of the spring drum until arrested by 25 the engagement of one of the column stops with the projected denominational stop.

The automatic platen shifting devices comprise a rock shaft 179 that bears at its forward end in a bracket 180 secured by a 30 screw 181 to the top plate, the rear end portion of said rock shaft bearing in a bracket 182 that is screwed at 183 to the top plate. Forward of the bracket 180 a crank arm 184 is secured to the rock shaft 179, 35 said crank arm having a hub portion 185 that is fixed to the shaft, and terminating at its free end in a forwardly bent portion 186 that underlies the shift rail 136 and is curved on its upper face so as to coöperate 40 smoothly therewith. Fixed to the rear end portion of the rock shaft 179 back of the bracket 182 is a crank arm 187 having a hub 188 which fits over and is fast on the rock shaft. The free end of said crank 45 arm 187 is connected by a vertically disposed link 189 which extends through an opening 119* in the top plate with a lever member 190 fulcrumed on a shouldered screw 191 secured to the front portion of 50 the bracket 184. The member 190 is cut out as indicated at 192 to fit over the barrel portion of said bracket and is provided with a rearwardly off-set lug or tooth 193. A trip 194 having a tooth 195 is pivoted on 55 the screw 191 in front of the member 190. A latch 196 pivoted at 197 to a fixed bracket 198 is connected by a draw spring 199 with the trip. The lug 193 and the tooth 195 are adapted to coöperate with a special column 60 stop 200 which differs from the ordinary column stop in that it is provided with a downward extension 200*, the path whereof is obstructed at times by the lug 193 and the tooth 195.

65 The platen is shown in lowercase position

in Fig. 6 and the shift rail 136 in Fig. 7 is correspondingly in lowercase position. Assuming that the automatic case shifting or platen shifting devices are arranged as in Fig. 7 and that the carriage is being restored from left to right to begin a new line it will be apparent that the extension 200* will engage with the lug 193 to swing the member 190 on its pivot, the motion of said member being transmitted through the link 189, crank arm 187, rock shaft 179 and crank arm 184, 186 to the shift rail 136 which will be elevated, lifting the platen frame and platen to uppercase position, the uppercase position of said platen being indicated by the dotted line in Fig. 6. The platen will be maintained locked in uppercase position by the latch 196 which will drop in behind the member 190 when it has been turned to effect the shift, said latch co-operating with the corner of said member and the two interlocking with each other to hold the platen locked in uppercase position until the advance of the carriage in printing direction brings the extension 200* into engagement with the tooth 195 of the trip 194. Said trip, as will be understood, has been moved so that the tooth 195 is in the path of the extension 200* at this time. As a result of the engagement of said stop portion with said tooth the trip will operate on the latch 196 to force it upward so that it will release the member 190, thus allowing the platen to return to normal or lowercase position. The movement of the platen 100 causes the member 190 and the trip 194 to be restored to normal position and the latch will thereby be forced to engage with the trip 194 back of the tooth 195 as in Fig. 7. The operation of the parts, it will be understood, is similar to those of the corresponding parts in the first described construction. The principle of operation is the same in both constructions and both constructions effect an automatic case shifting operation, 110 the relative movement between the platen and printing elements in the second case being caused by a movement of the platen whereas in the first case it is caused by a movement of the type bars. It will be observed that the automatic shifting devices do not interfere with the operation of the usual key controlled shifting devices. In the first described construction under operation of the key controlled devices the pin or stud 86 moves up away from the arm 85 and back into contiguity therewith without affecting the automatic devices connected to said arm. In the second described construction when the key operated shift devices are actuated the shift rail 136 moves upward away from and back toward the bent portion or extension 186 without affecting said extension or the connected parts. Further it will be noted that the work of shifting the 120 125 130

shiftable element upward in opposition to gravity is performed, in both constructions, by utilizing the power applied by the operator in returning the carriage, leaving to the carriage motor or spring merely the comparatively light work of operating the trip to release said element so that it may be restored largely through gravity. In both constructions, movement of the traveling element, carriage or platen is effective to cause operation of the case shifting mechanism. In both constructions also the movement of the operative traveling member is caused or effected in one direction by the carriage spring drum, and in the opposite direction by the power of the hand employed to retract the carriage.

Various changes other than those described may be made without departing from 20 my invention.

What I claim as new and desire to secure by Letters Patent, is:—

1. In a typewriting machine, the combination of a platen element, a coöperative printing element, said elements being relatively shiftable to effect a change of case and one of said elements being a traveling element, and automatically actuated case shifting means, said means being caused to operate 25 by movements of said traveling element.

2. In a typewriting machine, the combination of a traveling carriage, a platen thereon, printing instrumentalities, the platen and printing instrumentalities being relatively shiftable to effect a change of case, and case shifting means automatically actuated during traveling movements of said carriage and the operation of said means being due to such traveling movements.

40 3. In a typewriting machine, the combination of a traveling platen, a set of key actuated type bars each provided with a plurality of types, and means automatically operative for rendering the different types on the type bars effective, said means being caused to operate by traveling movements of said platen.

4. In a typewriting machine, the combination of a traveling carriage, a platen thereon, a motor tending constantly to cause traveling movements of said carriage, a set of key actuated type bars each provided with a plurality of types, and means automatically operative during traveling movements of 55 said carriage and rendered effective by said motor for rendering different types on the type bars effective.

5. In a typewriting machine, the combination of a platen, type bars provided with upper and lower case types, tabulating mechanism, and case shifting means automatically operating when said tabulating mechanism is actuated.

6. In a typewriting machine, the combination of a traveling platen element, a co-

operative printing element, said elements being relatively shiftable to effect a change of case, and case shifting means automatically operating at a predetermined point in the printing line and rendered effective by 70 traveling movements of said platen.

7. In a typewriting machine, the combination of a traveling carriage, a platen thereon, printing instrumentalities, the platen and printing instrumentalities being 75 relatively shiftable to effect a change of case, and case shifting means automatically actuated at a predetermined point in the travel of the carriage and rendered effective by traveling movements of said carriage.

8. In a typewriting machine, the combination of a platen element, a coöperative printing element, said elements being relatively shiftable to effect a change of case, automatically actuated case shifting means, 85 comprising two co-acting elements normally separated and key controlled case shifting means operative independently of said co-acting elements.

9. In a typewriting machine, the combination of a traveling carriage, a platen thereon, printing instrumentalities, the platen and printing instrumentalities being relatively shiftable to effect a change of case, case shifting means automatically rendered 90 effective by traveling movements of said carriage, and case shifting means controlled independently of traveling movements of said carriage.

10. In a typewriting machine, the combination of a platen, type bars each provided with two types, tabulating mechanism including a stop device, and case shifting means automatically actuated by said stop device.

11. In a typewriting machine, the combination of a platen, type bars provided with upper and lowercase types, tabulating mechanism including a traveling stop, and case shifting means automatically operative 110 by said traveling stop.

12. In a typewriting machine, the combination of a traveling carriage, a platen thereon, printing instrumentalities, said platen and said printing instrumentalities being relatively shiftable to effect a change of case, and case shift means automatically actuated during traveling movements of said carriage in one direction, said case shifting means being also automatically actuated 115 during traveling movements of said carriage in the opposite direction.

13. In a typewriting machine, the combination of a traveling carriage, a platen thereon, printing instrumentalities, said platen and said printing instrumentalities being relatively shiftable to effect a change of case, and case shift means automatically actuated during traveling movements of said carriage in one direction, said case shifting 125

130

means being also automatically actuated during movements of the carriage in the opposite direction to effect a relative shifting movement in the opposite direction from the 5 first case shifting movement and to restore said platen and said printing instrumentalities to their original case relationship.

14. In a typewriting machine, the combination of a traveling platen element, a co-operative printing element, said elements being relatively shiftable to effect a change of case, and case shifting means automatically operating at a predetermined point in the printing line, said case shifting means 10 automatically operating in reverse direction at a predetermined point during the return movement of the traveling platen to begin a new line.

15. In a typewriting machine, the combination of a traveling carriage, a platen thereon, printing instrumentalities, said platen and said printing instrumentalities being relatively shiftable to effect a change of case, case shifting means automatically 20 rendered effective by traveling movements of the carriage, and key controlled case shifting means operative at will.

16. In a typewriting machine, the combination of a traveling carriage, a platen thereon, printing instrumentalities, said platen and said printing instrumentalities being relatively shiftable to effect a change of case, case shifting means automatically 35 actuated at a predetermined point in the travel of the carriage and rendered effective by traveling movements thereof, and key controlled case shifting means operative at will at any point in the carriage travel.

17. In a typewriting machine, the combination of a carriage, a platen, a device connected to travel when said carriage travels, type bars provided with upper and lowercase types, and case shifting means automatically 40 operative by said traveling device.

45 18. In a typewriting machine, the combination of a carriage, a platen, a device adjustably mounted on said carriage, type bars provided with upper and lowercase types, and case shifting mechanism automatically 50 operative by said device.

55 19. In a typewriting machine, the combination of a carriage, a platen, a device adjustably mounted on said carriage, type bars provided with upper and lowercase types, and case shifting mechanism automatically 60 operative by said device to bring said upper and lowercase types into use in alternation.

20. In a typewriting machine, the combination of a traveling carriage, a platen thereon, a set of key controlled type bars, each type bar being provided with an upper-case type and a lowercase type, a device adapted to travel with said carriage, and case shifting means automatically operative 65

by said device during return movements of 65 said carriage to bring the uppercase types into use, said device being operative on said case shifting means during traveling movements of said platen in printing direction to again render the lowercase types operative. 70

21. In a typewriting machine, the combination of a traveling carriage, a platen thereon, printing instrumentalities, and case shifting and locking means automatically 75 actuated during traveling movements of said carriage.

22. In a typewriting machine, the combination of a traveling platen element, a motor constantly urging said element in one 80 direction, a co-operative printing element, and means for automatically shifting one only of said elements to change case, said means being rendered effective by said meter.

85 23. In a typewriting machine, the combination of a platen, a co-operative printing element, and means for automatically shifting one of said elements relatively to the other to change case and for maintaining 90 said shiftable element in shifted position.

24. In a typewriting machine, the combination of a traveling platen element, a co-operative printing element, means for shifting one of said elements to effect a change 95 of case, means rendered effective by movements of said traveling element, and means for locking said shiftable element in shifted position.

100 25. In a typewriting machine, the combination of a traveling carriage, a platen element thereon, a co-operative printing element, case shifting devices, case locking devices, and a device on said carriage for actuating said case shifting devices and said 105 case locking devices during movement of the carriage in one direction, said device being operative to unlock said locking devices during movements of said carriage in the opposite direction.

110 26. In a typewriting machine, the combination of a traveling carriage, a platen element thereon, a co-operative printing element, case shifting devices, case locking devices, and an actuating device on said carriage for actuating said case shifting devices and said case locking devices during 115 restoring movements of said carriage from left to right, said actuating device being operative during movements of said carriage in printing direction to unlock said locking devices.

120 27. In a typewriting machine, the combination of a traveling platen element, a co-operative printing element, automatically 125 actuated means for shifting one of said elements back and forth to effect a change of case, said means being rendered effective by

movements of said traveling element, and stops for limiting the back and forth movements of said shiftable element.

28. In a typewriting machine, the combination of a traveling carriage, a platen element thereon, a coöperative printing element, one of said elements being shiftable to change case, a lever member, connections between said lever member and said shiftable element, a device connected to travel with said carriage and coöperative with said lever member to actuate it and through it said shiftable member, a latch for said lever member, and a trip for said latch. 70
- 10 29. In a typewriting machine, the combination of a traveling carriage, a platen element thereon, a coöperative printing element, one of said elements being shiftable to change case, a lever member, connections between said lever member and said shiftable element, a device connected to travel with said carriage and coöperative with said lever member to actuate it and through it said shiftable member, a latch for said lever member, and a trip for said latch. 75
- 15 29. In a typewriting machine, the combination of a traveling carriage, a platen element thereon, a coöperative printing element, one of said elements being shiftable to change case, a lever member, connections between said lever member and said shiftable element, a device connected to travel with said carriage and coöperative with said lever member to actuate it and through it said shiftable member, a latch for holding said lever member in shifted position, and a trip for releasing said lever member, said trip being also operative by said device. 80
- 20 29. In a typewriting machine, the combination of a traveling carriage, a platen element thereon, a coöperative printing element, one of said elements being shiftable to change case, a lever member, connections between said lever member and said shiftable element, a device connected to travel with said carriage and coöperative with said lever member to actuate it and through it said shiftable member, a latch for holding said lever member in shifted position, and a trip for releasing said lever member, said trip being also operative by said device. 85
- 25 30. In a typewriting machine, the combination of a traveling carriage, a platen element thereon, a coöperative printing element, one of said elements being shiftable to change case, a lever member, connections between said lever member and said shiftable element, a device connected to travel with said carriage and coöperative with said lever member to actuate it and through it said shiftable member, a spring pressed pivoted latch, and a spring pressed pivoted trip, said latch being effective to lock said lever member and hold said shiftable member in shifted position and said trip being operative by said traveling device to render said latch ineffective on said lever member. 90
- 30 30. In a typewriting machine, the combination of a traveling carriage, a platen element thereon, a coöperative printing element, one of said elements being shiftable to change case, a lever member, connections between said lever member and said shiftable element, a device connected to travel with said carriage and coöperative with said lever member to actuate it and through it said shiftable member, a spring pressed pivoted latch, and a spring pressed pivoted trip, said latch being effective to lock said lever member and hold said shiftable member in shifted position and said trip being operative by said traveling device to render said latch ineffective on said lever member. 95
- 35 31. In a typewriting machine, the combination of a traveling carriage, a platen element thereon, a coöperative printing element, one of said elements being shiftable to change case, a lever member, connections between said lever member and said shiftable element, a device connected to travel with said carriage and coöperative with said lever member to actuate it and through it said shiftable member, a pivoted latch, a pivoted trip, and a draw spring connected to said latch and to said trip, said trip being operative by said traveling device to unlock said latch when the same is operative. 100
- 40 32. In a typewriting machine, the combination of a traveling carriage, a platen element thereon, a coöperative printing element, one of said elements being shiftable to change case, a lever member, connections between said lever member and said shiftable element, a device connected to travel with said carriage and coöperative with said lever member to actuate it and through it said shiftable element, one of said elements being shiftable to change case, a lever member, connections between said lever member and said shiftable element comprising a link and a second lever, said second lever being operative on said shiftable member being rendered effective for such purpose by movements of said traveling carriage. 105
- 45 33. In a typewriting machine, the combination of a traveling carriage, a platen element thereon, a shiftable type bar support, type bars thereon, a lever member, connections between said lever member and said type bar support, a device mounted on the carriage and coöperative with said lever member to actuate it and through it to actuate said shiftable support, a latch for holding said lever member in shifted position, and a trip for releasing said lever member, said trip being also operative by said device. 110
- 50 34. In a typewriting machine, the combination of a traveling carriage; a platen element thereon; a shiftable type bar support; type bars thereon; a lever member; connections between said lever member and said type bar support, said connections comprising a link, a bell crank, a rock shaft, a crank arm thereon, a second link connecting said crank arm with said bell crank, and a second crank arm secured to said rock shaft and coöperative with a projection on said shiftable support; a device mounted on the carriage and coöperative with said lever member to actuate it; a latch for holding said lever member in shifted position; and a trip for releasing said lever member, said trip being also operative by said device. 115
- 55 35. In a typewriting machine, the combination of a traveling carriage; a platen element thereon; a shiftable type bar support; type bars thereon; a lever member; connections between said lever member and said type bar support, said connections comprising a link, a bell crank, a rock shaft, a crank arm thereon, a second link connecting said crank arm with said bell crank, and a second crank arm secured to said rock shaft and coöperative with a projection on said shiftable support; a device mounted on the carriage and coöperative with said lever member to actuate it; a latch for holding said lever member in shifted position; a trip for releasing said lever member, said trip being also operative by said device; and key controlled connections for shifting said segment independently of said first recited connections. 120
- 60 36. In a typewriting machine, the combination of a traveling carriage, a platen element thereon, a carriage spring drum key controlled type bars, a shiftable type bar support, and means for shifting said support, said means being automatically operative during traveling movements of said carriage and rendered effective by said spring drum. 125
- 65 36. In a typewriting machine, the combination of a traveling carriage, a platen element thereon, a carriage spring drum key controlled type bars, a shiftable type bar support, and means for shifting said support, said means being automatically operative during traveling movements of said carriage and rendered effective by said spring drum. 130

87. In a typewriting machine, the combination of a traveling carriage, a platen thereon, key controlled type bars, a shiftable type bar support, tabulating mechanism, and means for shifting said support, said means operating automatically when the tabulating mechanism is actuated. 35
88. In a typewriting machine, the combination of a traveling carriage, a platen thereon, a carriage spring drum key controlled type bars, a shiftable type bar support, and means for shifting said support, said means operating automatically at a predetermined point in the printing line 40
- 10 rendered effective by said spring drum, said predetermined point being variable at will. 45
89. In a typewriting machine, the combination of a traveling carriage, a platen thereon, key controlled type bars, a shiftable type bar support, means for shifting said support, said means operating automatically during traveling movements of the carriage at a predetermined point in the printing line, said predetermined point being variable 50
- 15 at will, and key controlled means for at will shifting said support independently of movements of the carriage. 55
40. In a typewriting machine, the combination of a traveling carriage, a platen thereon, type bars each provided with an uppercase type and a lowercase type, a shiftable type bar support, tabulating mechanism including a stop device, and means for 60
- 20 shifting said support automatically operative by said stop device. 65
41. In a front-strike typewriting machine, the combination of a traveling carriage, a platen thereon, type bars each provided with two types, a vertical shiftable type bar segment, key controlled tabulating mechanism including an adjustable stop on said carriage, and means for shifting said segment up and down, said means being automatically controlled by said stop. 70
42. In a typewriting machine, the combination of a traveling carriage, a platen thereon, key controlled type bars each provided with two types, a shiftable type bar support, key controlled tabulating mechanism including a stop on said carriage, and means for shifting said support, said means being operative by said stop, said stop operating during return movements of said carriage to shift and lock said support in uppercase position and being operative when the tabulating mechanism is operated to release or unlock said means permitting said support to be automatically restored to normal or lowercase position. 75

Signed at Syracuse, in the county of 60
Onondaga, and State of New York, this
26th day of March A. D. 1913.
